UNITED STATES PATENT OFFICE

2,525,215

GIRDLE

Jan J. Erteszek, Los Angeles, Calif.

Application November 4, 1948, Serial No. 58,303

1 Claim. (Cl. 2—37)

1

My invention relates to ladies undergarments, particularly to girdles and foundation garments, and the principal objects of my invention are, to generally improve upon and simplify the construction of existing forms of girdles and the like, to provide a girdle composed of elastic and non-elastic parts arranged and combined so as to snugly fit the wearer's body and at the same time yield readily to all movements of the body and resisting undue strains and pressures and, further, providing a smooth, yielding foundation for the wearer's outer garments.

A further object of my invention is, to provide a girdle having in its rear skirt portion, an elastic panel arranged to stretch vertically and extending from the lower edge of an upper non-elastic back panel, downwardly from the lower portions of the buttocks over the upper portions of the thighs, so that the non-elastic upper panel confines the buttocks while the lower elastic panel will stretch vertically and move with the underlying parts of the body as the wearer sits down, arises from a sitting position, or bends the body forwardly, rearwardly or laterally.

My improved garment structure may be employed with equal advantages in foundation garments other than conventional girdles, for instance, panty girdles, bathing suits and the like.

With the foregoing and other objects in view, my invention consists in certain novel features of construction and arrangement of parts which will be hereinafter more fully described and claimed and illustrated in the accompanying drawing, in which:

Fig. 1 is a rear perspective view of the garment.

Fig. 2 is a front perspective view.

As seen in the drawing, the garment is generally tubular in shape, gradually flaring or increasing in diameter toward its lower end, so as to fit snugly upon the lower portion of the wearer's body, the buttocks and upper portions of the thighs.

Referring by numerals to the drawing, 10 designates the front panel, preferably of non-elastic fabric, with its outer face decorated as desired, 11 the side panels of elastic material adapted to stretch horizontally and/or vertically, 12 the rear upper panel of non-elastic material disposed between the upper portions of the side panels 11, and 13, the rear lower panel of elastic material stretchable vertically and disposed between the lower portions of side panels 11, below upper back panel 12.

The meeting edges of the panels just described

2

are united, preferably by a row or rows of stitching and if desired these seams may be overlaid by narrow strips 14 of lace, decorative tape, or the like.

5 Formed in the upper front portion of the side panel which overlies the left side of the wearer is a vertical slit 15, fitted with a flexible sliding fastener 16, generally termed a "zipper," thus facilitating the putting on and taking off of the garment.

Located in the upper central portion of rear panel 12 is a V-shaped panel 17 of elastic material stretchable horizontally, thus enabling the waist encircling upper end of the garment to stretch circumferentially while being placed upon or removed from the body.

Depending from the lower edges of the front panel 10 and lower rear panel 13 are conventional hose supporters 18.

20 In my improved girdle, the front and rear panels 10 and 12 combine with the elastic side panels 11 to provide a snug form-fitting garment, with said panels 10 and 12 serving as firm non-stretching supports for the wearer's abdomen and buttocks, with the lower elastic back panel 13 extending downwardly from the buttocks over the rear portions of the thighs, so as to follow the movements of the latter without discomfort to the wearer, while bending the body forward,

30 rearward, or while sitting down or arising from a seat. In other words, my improved construction, particularly the elastic lower back member imparts the much desired lower back stretch to girdles and similar foundation garments and at the same time, enables garments of ample strength to be produced with very light or sheer non-elastic panels.

It is to be noted that the seam or joint between the lower edge of upper back panel 12 and upper edge of lower back panel 13 is sinusoidal in form and arranged so that the end portions of said lower panel are wider than the central portion. This particular arrangement is effective in providing for increased vertical stretching areas for those portions of elastic panel 13 which overlie the lower portions of the wearer's buttocks and upper rear portions of the thighs, which parts exert the greatest stretching strains

45 on both panels, and thus the stress of such strains are more uniformly distributed and the life or periods of service of both panels, is increased.

50 Thus it will be seen that I have provided a girdle or foundation garment that is simple in structure, inexpensive of manufacture and very

effective in performing the functions for which it is intended.

Minor changes in the size, form and construction of the various parts of my improved girdle may be made and substituted for those herein shown and described without departing from the spirit of my invention, the scope of which is set forth in the appended claim.

I claim as my invention:

A girdle or like foundation garment comprising a substantially tubular body gradually flaring toward its lower end, a non-stretching panel in the upper rear portion of said body, a horizontally stretchable triangular panel in the upper portion of said non-stretching upper panel, with its upper edge forming a portion of the waistband of the girdle, a vertically stretchable panel in the lower rear portion of said body and a flexible non-elastic front panel extending from top to bottom of said body and side panels ex- 20

tending from top to bottom of said body, with their side edges secured respectively to the side edges of said flexible front panel and to the side edges of said non-stretching upper rear panel and the side edges of said vertically stretchable lower rear panel, which side panels are composed of material which is stretchable vertically and horizontally.

JAN J. ERTESEK.
